UNITED STATES PATENT OFFICE.

WILLIAM H. IVERSON, OF OSCEOLA, WISCONSIN, ASSIGNOR OF ONE-HALF TO HOMER F. EHLE, OF MINNEAPOLIS, MINNESOTA.

BAG HOLDER.

1,405,846.

Specification of Letters Patent. Patented Feb. 7, 1922.

Application filed May 13, 1918. Serial No. 234,088.

To all whom it may concern:

Be it known that I, WILLIAM H. IVERSON, a citizen of the United States, residing at Osceola, in the county of Polk and State of Wisconsin, have invented certain new and useful Improvements in Bag Holders; and I do hereby declare the following to be a full, clear, and exact description of the invention, such as will enable others skilled in the art to which it appertains to make and use the same.

My present invention has for its object to provide an extremely simple and highly efficient bag holder, and to such ends, generally stated, it consists of the novel devices and combinations of devices herein-after described and defined in the claim.

My improved bag holder is adapted for general use wherever it is necessary to hold a bag in an open position for filling, either by hand operations or from a machine, but is especially adapted for the first noted use. It is adjustable both to bags of different length and to bags of different cross dimensions. It is adapted to be quickly adjusted, and moreover, without different setting, is capable of holding bags that vary a great deal in cross dimensions, or width. After it is set, it is capable of being operated to grip or to release a bag simply by manipulation of a foot lever.

In the accompanying drawings which illustrate the invention in its preferred form, like characters indicate like parts throughout the several views.

Referring to the drawings,

Fig. 1 is a front elevation of the improved bag holder;

Fig. 2 is a side elevation of the same;

Fig. 3 is a horizontal section taken on the line 3—3 of Fig. 1;

Fig. 4 is a detail partly in side elevation and partly in vertical section showing a portion of the column, the head movable thereon, the actuating rod in the said head and a co-operating stop plate; and

Fig. 5 is a detail looking at the rear face of the actuating rod.

The bag holder comprises a suitable column or upright 6 preferably in the form of a stiff flat steel bar braced by a truss rod 7 and rigidly secured to a base plate or board 8. This base 8 preferably is provided at one edge with a pair of projecting wheel brackets 9 having small truck wheels 10 so

that the device may be used as a truck to wheel away a filled bag, as will presently more clearly appear.

Also, rigidly secured to the base 8 is a bracket 9 which, at one end is in the form of an upright yoke 10, one side of which is formed with ratchet-like teeth 11. A foot lever 12 is pivoted to the bracket 9 by a bolt 13 which also preferably connects the said bracket to the lower portion of the column 6. The lever 12 is provided with a dog-acting lug 14 that is engageable with and disengageable from the ratchet teeth 11 by slight lateral movement of the lever 12. Mounted to slide telescopically on the upper portion of the column 6 is a pair of heads 15—16 which are preferably castings made in duplicate. The lower head 16 is arranged to be adjustably locked to the column 6 by a set screw 17 while the upper head 15 is free to slide vertically on the said column. The relatively movable upper head 15 has a rearwardly projecting cap screw 18 that adapts it to be adjustably secured to a notched bar or rod extension 19. This notched bar 19 has a longitudinal slot 19^a through which the cap screw 18 is passed, and preferably, and as shown, a rectangular washer 18^a is placed on this screw 18, and by the head thereof, is seated in the proper notch of the bar 18 so as to effectually prevent slipping of the said bar in respect to the head 15.

The lower end of this bar 19 is rigidly secured to the upper end of an actuating rod 20, the lower end of which is adapted to be pivotally held in any one of several longitudinally spaced holes 21 in the foot lever 12. This rod 20 is made with a bend, as best shown in Fig. 1, so that it will spring considerably under the downward force applied thereto from the lever 12.

To the opposite sides of the lower adjustable but relatively fixed head 16, is pivoted a pair of bag holding levers 22, 100 which, at their outer or free ends, are provided with laterally projecting arms 23 that terminate in retaining fingers 24 preferably equipped at their ends with barbs 25. Preferably, the said parts 22, 23, 24 and 25 are formed integral from a single flat bar and it will be noted that the place where the arms 23 join with the outer ends of the levers 22, there is a projecting U-shaped bend 23^a that serves as a lug to hold a cor- 110

ner of the bag when the bag is in position with its mouth held open by the bag holder. Links 26 are pivoted to the opposite sides of the movable head 15 and to the intermediate portions of the respective levers 22.

The numeral 27 indicates a sheet metal shield or deflecting plate adapted to be detachably hung on the upper portion of the column, and as shown, provided with a rearwardly bent upper edge flange 28 that is perforated, so that it will slip onto the upper end of the said column. In Figs. 1 and 4, this shield is shown as slightly raised from its operative position, but in its operative position it will drop until its flange 28 rests upon the upper head 15.

The lower so-called relatively fixed head 16 should be adjusted so that when the sack is held with its mouth spread open by the arms, its bottom will rest on the platform or base 8. In applying the sack to the holder, its open mouth is spread and attached over the four corners afforded by the two lug portions 23, and when thus applied, the open mouth 25 of the bag will be held in rectangular formation so that the grain or other material may be readily shoveled or otherwise delivered into the sack. To secure the sack spread open in this manner, the operator steps on the free 30 end of the foot lever 12, and by lateral pressure, interlocks its dog 14 with one or the other of the ratchet teeth 11. When the sack has been filled, the lever is released by cranking or pressing laterally, so as to disengage 35 its dog 14 from the ratchet tooth and when this is done, the sack can, of course be easily removed from the holding arms. The bend or spring in the connecting rod 20 permits the lever 12 to be properly engaged with the 40 ratchet teeth and puts the levers and holding arms under a spring tension to hold the sack open.

Of course, there is such movement of the

levers 22 that sacks varying considerably in transverse dimension or cross section may be held without varying the adjustment of the relatively fixed lower head 16.

The shield or deflecting board 27 will ride upon the upper relatively movable head 15 and its lower edge will overlap within the sack 45 and direct into the sack any material that may be thrown or shoveled against said shield. For sacks of different width or transverse dimension, different shields may be employed, if desired, and when several are employed, the one may be easily substituted for the other.

When the sack is filled and while it is still held by the arms, the device may be used as a truck to wheel the sack to a desired point 60 distant from the point of filling.

This improved sack holder may be made at comparatively small cost, and in practice, has been found highly efficient for the purposes had in view.

What I claim is:

A bag holder comprising a vertical standard, bag holding means on the standard including a movable head, a foot lever pivoted to the standard and extended to one side 70 thereof, an actuating rod of spring metal connecting the movable head to the foot lever, said rod extending downward for a portion of its length parallel to the standard and then extending at an angle to said standard and 75 being secured to said foot lever at some distance from the standard whereby a resilient action is given to the bag holding means when the foot lever is moved to actuate the same.

In testimony whereof I affix my signature in presence of two witnesses.

WILLIAM H. IVERSON.
